BICYCLE HANDLEBAR ATTACHMENT

Harry Golden, New York, N.Y., assignor to Ideas for Auto & Bike Specialties, Inc., New York, N.Y., a corporation of New York

Filed July 30, 1963, Ser. No. 76,044

Term of patent 7 years

(Cl. D90—11)

The portions shown in broken lines in FIGURE 1 are included for illustrative purposes only.

I claim:

The ornamental design for a bicycle handlebar attachment, as shown and described.
